Application May 3, 1950, Serial No. 159,710

Claims priority, application Sweden May 4, 1949

5 Claims. (Cl. 266—21)

1

In the usual sintering processes the charge, after fuel has been added thereto, is placed on a grate and ignited, while a fan draws air preferably downwards through the grate. The charge is burnt in layers, and the gas escapes with a gradually rising temperature, whereby considerable heat is lost. In the last phase of the burning the further drawback is encountered that loose particles are entrained by the gas and occasion wear in the conduit system. Because of the expensive repeated ignition of new charges it is necessary to work with rather thick charge layers and hence with a relatively high suction which increases the cost of the sintering equipment.

It is known, however, to avoid the drawback of repeated ignition of new charges by using two grate pans placed upon each other and at intervals to exchange these with freshly charged pans in a cyclic sequence. With downward draft this is effected in the manner that at first, when the upper pan is burnt down, this pan is removed and the lower pan is moved aside, whereafter a new pan is placed at the bottom and the previously lowermost pan is placed on top of it. When the burning of this latter pan is then finished, the charge in the lower pan is heated by the exhaust gases and radiant heat from the upper pan and thereby ignited. However, with this method the exchanging step becomes rather troublesome and no ideal heat utilization is obtained, since when using only two pans the exhaust gases will still have to escape at a rather high temperature, neither will the drawback of suspended particles be avoided.

If on the contrary more pans are used, i. e. a complete stack of for example 3 to 6 pans, the heat economy can be considerably improved, since the heat of the downwardly moving exhaust gases can still be used for heating the charge of freshly inserted pans at the bottom of the stack, which charge also withholds suspended particles from the burning layers, while at the same time the incoming combustion air can be preheated by passing through pans which have burnt down.

It may be mentioned that it is also known in connection with treatments of solids with gases, including roasting processes, to use a stack of grate pans with downward draft and resting on a bottom box and at intervals to exchange one pan at a time. With this construction the gas enters the uppermost pan through a fixed dome and leaves through the bottom box. Exchanging is effected in the manner that the bottom box is

2

lowered somewhat more than the height of one pan, the stack following a short distance so that the uppermost pan gets clear of the dome and can be removed laterally, whereafter the stack remains stationary at a suitable level above the bottom box for permitting a freshly charged pan to be introduced in-between. By the lowering of the bottom box the connection of the same with the gas outlet is interrupted, and in the case of a combustion process such as roasting, the combustion will have to be initiated by using heated oxygen-containing gas. This again requires a low ignition temperature, and in the case of powdered material a preceding agglomeration or briquetting will be required.

A drawback which is common to all the known processes referred to is that the gas current through the charge must be interrupted during each exchanging step, which apart from retarding the process may in many cases cause undesirable secondary reactions, particularly since a considerable time is required for the exchanging step in view of the large furnace areas and consequent pan dimensions required when operating on a commercial scale. Another drawback of known structures is the heat loss which occurs partly in connection with the exchanging intervals and partly by heat conduction through the pan walls, as well as the consequent uneven combustion. Further the discharge of the pans may involve difficulties because the burnt charge is likely to stick to the hot grates.

The present invention relates to a process and an apparatus for draft sintering and has for an object to avoid the above mentioned drawbacks encountered with known structures and to permit a continuous sintering to be effected in a particularly economical and favorable manner. A stack of grate pans is used which is open at the top so that the uppermost pan is accessible for the initial ignition. At the bottom the stack is connected to a suction device, and the pans are exchanged successively so that constantly a lower pan in the stack is preheated and ignited by utilizing the heat developed in the superposed pans. The process is primarily characterized in that in each exchanging step a pan at the top of the stack, which pan has burnt down and been cooled by the incoming air while preheating the same, is moved aside in order to be discharged and charged anew while a freshly charged pan is introduced laterally under the stack in a lifted position of the latter.

The apparatus according to the invention, which is designed for carrying out this process

and which apart from the shaft furnace composed of roast pans with appurtenant suction box, comprises feeding, discharging and conveying means for the pans, is characterized by a device for lifting the pan stacks at intervals to a level so as to permit a freshly charged grate pan to be introduced between the stack and the suction box and for lowering the stack onto the new pan and the latter onto the suction box, in combination with a device adapted, before the arrival of the stack in its lowermost position, to catch the uppermost pan of the stack on a conveying structure for lateral removal from the stack.

When using the invention the several advantages are obtained which have been referred to above and are due to the use of a stack of grate pans in which the heat content of pans which have burnt down is used for preheating the combustion air, and the heat content of the exhaust gases is used for heating freshly charged pans, the latter pans producing a filtering action by retaining suspended particles derived from the burning layers, and the initial ignition does not involve difficulties. Further, when using the invention, the pans may be exchanged during relatively short time interval, the connection between the suction means and the pan stack being interrupted only in the intervals required for lifting the stack and introducing the new pan, since the tightening between the latter and both the superposed pan and the suction box is effected during the initial lowering movement and without any interruption of the connection between the gas outlet and the suction box, which latter may remain stationary. Further it is possible when using the invention to maintain the gas current through the pan stack uninterrupted during the exchanging step by effecting the insertion of the new pan in the bottom of the stack in a space which is shut off from the surrounding air.

Heat losses to the outside and burning of the charge onto the grate bars may be minimized according to the invention by maintaining through the walls and grate bars of the pans within the stack a circulating current of cooling medium, the heat of which may then be utilized.

To prevent uneven sintering due to heat conduction from the charge to the pan walls the latter are preferably provided with heat insulation at the inside.

Further features and advantages will appear from the following specification, reference being had to the drawings which illustrate a preferred embodiment of the apparatus.

Fig. 1 is a diagrammatic side view of the apparatus on a small scale and partly in section.

Fig. 2 is a corresponding top view in which structures at the top of the pan stack have been omitted for the sake of clearness.

Fig. 3 is an end view of a pan emptying device on a somewhat larger scale.

Fig. 4 is a top plan view of a grate pan on a still larger scale.

Fig. 5 is a fragmentary view on the same scale as Fig. 4 of the pan stack with the surrounding casing in section substantially along the line V—V in Fig. 2.

Fig. 6 is a cross sectional view on a still larger scale of an end wall of a grate pan taken along the line VI—VI in Fig. 4 and of a corresponding connecting means for a cooling water circuit.

Fig. 7 is a cross sectional view on the same scale of the lowermost portion of a side wall of a grate pan and the top of the corresponding side wall

5 of a pan located below the same (indicated by the line VII—VII in Fig. 4).

Fig. 8 illustrates two possible grate bar cross sections.

10 The drawings illustratively show a stack of five grate pans 1 resting on a circumferential flange 2 of a funnel-shaped bottom suction box 3 equipped with a suction pipe 4 and an outlet 5 which may be closed for example with a sluice structure. For conveying the pans away from the top of the stack emptying the pans, and conveying freshly charged pans toward the stack conveyor means comprising plurality of rollers,

15 6, 7, 9, 10 and 11 are provided which co-operate with longitudinal flanges 12 on both sides of the pans. The rollers 6 at the top of the stack are mounted on two pendulum members 13, which can be moved laterally outwardly by means of a pressure cylinder 14 (Fig. 5) in order to avoid interference with the laterally extending flanges 12 of the uppermost pan when the stack is lifted. The several sets of rollers, which may be driven in groups, may be operated by electric motors or other conventional driving means (not shown).

20 19. The rollers 1 are placed at the same level as the rollers 6 and serve to convey finished pans to a tilting emptying device 15 comprising a discharge funnel 16, which by means of annular rims 17 is rotatable on rollers 18 of a lowering structure

25 19. The structure or transfer 19 comprises a frame adapted to be raised and lowered by means of pressure cylinder 20 and preferably propped by rollers 21 engaging vertical rails 22. Apart from the driven grooved rollers 8, onto which the

30 35 pans are passed with their lateral flanges, the tilting structure 15 also comprises a set of grooved rollers 23, which engage the top side of these flanges and serve to keep the pan in position when the latter is turned 180° by means of the tilting device so as to be emptied through the funnel 16,

40 the latter engaging with a circumferential flange the top of the pan walls. By means of the lowering structure 19, while being turned upside down and back again by the rollers 18 the pans are lowered from the level of the rollers 1 to the level of the rollers 9 and 10, which are adapted

45 to support the pans at a slightly higher level than that of the lowermost pan of the stack. The movement of the pans out of the tilting device 15 after they have regained their normal position is effected by the rollers 8 and the rollers 9, which move the pan into position under the feeding or charging device 24. This device consists of for

50 example two oppositely threaded screw conveyors indicated at 25, which feed the charge inwards over the pan from both sides through passages 26 which in the central area over the pan are each provided with a pair of pivoted bottom flaps operated by means of a link mechanism from a pair of pressure cylinders 28 for each screw conveyor.

55 By means of the feeding device the pans are conveniently filled substantially to the brim, scraping devices or the like being used if desired for evening the charge so that it attains a substantially equal level above the pan grate 30.

When using tilting and feeding devices of the construction described, it is possible to effect discharging and charging so rapidly that the time required from the moment when a pan is removed from the stack and till the moment when it is again ready for insertion at the bottom of the stack will not be longer than that which the process will usually require between two consecutive exchanging intervals.

60 A casing or enclosure 31 surrounds the suction

box 3 and the lower part of the pan stack and defines a low pressure zone which communicates with an air lock chamber 32 in which the conveyor rollers 19 are mounted and which is provided with a couple of vertically movable air lock gates 33 and 34 operated by pressure cylinders 35 and 36 respectively. Upon the arrival of a freshly charged pan from the feeding device 24, the gate 33 is open and the gate 34 closed, and thereafter, to permit insertion of the pan beneath the bottom of the stack the gate 33 is kept closed when the gate 34 is opened. This makes it possible to introduce the pans into the casing 31 without the admission of outer air. To facilitate operation of the gates the air lock chamber 32 may be equipped with pressure-equalizing by-pass conduits provided with cocks 37 and 38.

The rollers 11 which feed freshly charged pans beneath the bottom of the stack from the air lock chamber 32 are rotatably mounted on a pair of parallel beams 38 extending along both sides of the suction box 3 within the casing 31 and adapted to be raised and lowered by pressure cylinders 40. Each of the beams 38 also carries two upwardly extending supporting members 41 (Fig. 5) for pivotally mounted lifting arms 42, adapted to engage the bottom side of the lateral flange of the lowermost pan of the stack in order to raise the stack of pans when the beams 38 are raised. Each lifting arm 42 is formed as a lever with a guiding roller 43 at one end thereof which engages a vertical rail 44 during the lifting movement. When the beam is lowered relative to the newly inserted pan, the lifting arms 42 may turn pivotally to move freely past the flange thereon.

At the top the casing 31 is formed with a rectangular pressure sealing shaft 45 surrounding the stack over a somewhat greater height than the vertical dimensions of one pan. For air-tight engagement with the shaft 45 the pans 1 are formed with flanges extending around their entire peripheries, the side flanges 12 merging through rounded corners with end flanges 46. At their outer edges the flanges 12, 46 may be equipped with resilient packing strips 47 for example of asbestos steel and as shown in Figs. 6 and 7 with an internal hollow space. In the preferred embodiment in which the walls and grate bars of the pans are made hollow for passing cooling water or other cooling medium therethrough, the hollow space of the packing strips may communicate with that of the pan walls for example through a conduit 48 provided with cock 49 so as to provide a resilient tightening pressure.

The grate 30 of each pan is preferably placed at a considerable distance above the bottom edge of the pan, as shown in Fig. 5, in order that even when the underlying pan has been filled to the brim an ignition chamber will be provided above the same, whereby a uniform heating of the charge of an underlying pan may be obtained by heat radiation from the overlying pan supplementing the hot downward gas current, since both radiation shadows and lee areas may be equalized in the ignition chamber. Further, in order to obtain the best possible effect in this respect, grate tubes of circular cross section may be used as shown at 38a in Fig. 8, or, if desired, an extension may be welded thereto so as to afford a streamline shape as shown at 38b. These tubular grate bars which in the construction shown extend longitudinally of the rectangular pan may be slidably supported in the end walls of the pan in order to accommodate dimensional

5 changes caused by thermal expansion and contraction. As shown in Fig. 6, the end of the hollow grate bar 30 is provided with a gland member 50 which engages resilient packing 51 to form a fluid tight seal, thereby preventing leakage of cooling fluid circulating through the grate bars and the passages formed in the walls of the pan.

15 The pan walls are thermally insulated from the charge by means of an internal lining 52 for example of asbestos, which may be protected by a plate 53 of stainless steel or an iron plate coated with stainless steel.

20 For sealing against air leakage through the joints between the pans of the stack, the pan walls, which generally are of hollow rectangular cross section, are provided at the top with a longitudinal rib 54 (Figs. 4 and 7) fitting between a pair of ledges 55 on the bottom side of the overlying pan and engaging packings 56 withheld by the ledges. A rib identical to the rib 54 may also be provided on the flange 2 of the suction box 3.

25 In order to transfer heat from the pans and prevent burning of the sintered material onto the grate bars, a continuously circulating current of cooling medium such as water is maintained flowing through the hollow walls and grate bars of the pans within the stack. By means of a pump 57 in an external portion of the cooling circuit this medium is forced through a conduit 58 with cock 77 into the lowermost pan through a connection device in the suction box flange 2 and flows through all the pans in series and out from the uppermost pan through a connection device 59 into the outer circuit where it returns through a flexible conduit 60 and a heat exchanger 61 to the suction side of the pump. The connecting device 59 can be moved up and down by a pressure cylinder 62. In the heat exchanger 61 the heated cooling water delivers its heat indirectly to a circuit 63 in which it may be utilized in any desired manner.

30 The cooling water enters each pan through a sleeve 64 (Fig. 6) threaded into the bottom of one of the hollow end walls thereof and provided with a spring-actuated check valve 65 and leading into an inlet chamber 66 which is closed at the top and both sides by dividing walls 67 (Fig. 6) and 68 (Fig. 4) respectively. From the inlet chamber 66 the water then flows through the grate tubes 30 into the opposite end wall of the pan and then back through the side walls into the space 69 above the dividing wall 67. From this space the water leaves the pan at the top through a spring-actuated valve 70 which is normally closed, but which, when positioned within the stack, is kept open by engagement of upward projections 71 of the valve member 70 with the sleeve 64 of the overlying pan or, for the uppermost pan, by engagement with a corresponding sleeve 72 of a check valve 73 in the connecting device 59. In a similar manner the sleeve 64 of the lowermost pan opens a valve in the connecting device of the suction box flange 2. This valve has not been shown, since it may be similar to the valve 70. A sealing against leakage of cooling water when passing from one pan to another is obtained by an annular upwardly extending projection 74 at the outlet from each pan (and also on the suction box flange), which fits into a corresponding recess surrounding the lower end of the sleeve 64 of the overlying pan, and likewise surrounding the sleeve 72 of the outlet connection member 59 above the top of the stack, and engages an annular gasket 75 or 76 respectively.

The operation of the apparatus is as follows: During the intervals between the exchanging pans in the stack all the pans except the one which is in transit and being emptied and filled again are at rest within the stack which assumes the position shown in Figures 1 and 5, a constant downward draft through all the grates of the stacked pans in series is maintained by means of the suction box 3 connected to the suction conduit 4, and the cock 77 in the water circuit is open, the outlet connection member 55 being at the same time kept pressed against the uppermost pan by the pressure cylinder 62, so that all the cooling water valves of the pans of the stack are likewise kept open and hence the cooling water flows through the pans in series. In the uppermost pan of the stack where fresh combustion air enters from the top, the air is preheated in the course of its passage through the uppermost pan which has burnt down, thereby cooling the latter and then causes combustion and consequent sintering of the charge in the hottest intermediate zone of the stack, and in the lowermost zone of the stack the combustion gases are cooled while passing through the charge of the pan or pans last inserted, and these lowermost pans are at the same time preheated and ignited partly by heat transfer from the combustion gases and partly by heat radiation from above.

At the moment when an exchange of pans is to be initiated, a freshly charged pan is ready in the air lock chamber 32, and the gates 33 and 34 are closed. Now the cock 77 of the water circuit is closed (or if desired the pump 57 may be stopped), the pressure at the top of the piston within the outlet connection control cylinder 62 is removed and the stack lifting cylinders 40 are connected for lifting the beams 39, while the air lock cylinders 36 after opening the pressure equalizing cock 38 are connected for lowering the air lock gate 34. In this manner, the entire stack of sintering pans is lifted off from the suction box 3 by means of the pivotally mounted lifting arms 42 during the upward movement of the latter. However, suction through conduit 4 is maintained, and in spite of the fact that the stack is no longer connected directly to the suction box 3, the downward draft in the stack will still be maintained because of the reduced air pressure within the casing 31, with which the suction box 3 still communicates, is shut off from the outer air by means of the outer air lock gate 33 and the pressure sealing engagement between the shaft walls 45 and the circumferential flange on the pan or pans contacting shaft walls. By shutting off the water circuit by means of the cock 77, the check valves 55 close and thereby prevent the cooling water from escaping, and likewise the connecting device on the suction box flange is closed by the lifting of the stack therefrom. During the upward movement of the stack water outlet connection device 59 is lifted off from the uppermost pan by means of the pressure cylinder 62, whereby the outlet valve 71 of this pan closes so that the water space of the uppermost pan is completely shut off from the outside. Further, during the lifting movement the pendulum members 13 are moved laterally outwards by means of the pressure cylinders 44 so that the lateral flange 12 of the uppermost pan can pass the rollers 6, whereafter these rollers are again turned back into normal position under the flange, as seen in Fig. 5 in which the upper-

most position of the pan has been indicated in dash-and-dot lines.

When the beams 39 have arrived in the uppermost position the rollers 11 are level with the air lock rollers 10 which are then operated for inserting the newly charged pan into the space between the bottom of the stack and the top of the suction box 3. When then this freshly charged pan has arrived in the required position, the lowering of the beams by means of the cylinders 40 is initiated, whereby the new pan will engage the suction box 3, the uppermost pan is caught by the rollers 6 and the previously lowermost pan of the stack shortly afterwards will engage the new pan. The pan which has been lifted off is at once moved aside by means of the rollers 6, and the water outlet connecting member 59 is again pressed down onto the now uppermost pan, whereby the water circuit is again completed so that the cock 77 may be opened anew. At the same time the air lock cylinders 36 are operated for upward movement and as soon as the gate 34 has been closed thereby and likewise the low pressure equalizing cock 38 has been closed, the atmospheric pressure equalizing cock 37 may be opened and the outer gate 33 lowered so that the air lock chamber is ready to receive the removed pan as soon as the latter has been emptied and filled anew by means of the emptying and charging devices 15 and 24 respectively.

The pressure cylinders shown may be driven in any usual known manner with either pneumatic or hydraulic pressure and controlled by suitable valves. The operation of these valves as well as the starting and stopping devices for the motors of the rotating rollers etc. and of the cock 77 may conveniently be automatic. Means for this purpose have not been shown since they may be of usual known construction. The operation thereof may be time-controlled or the exchanging step may be initiated by means of sensing means responsive to the temperature of any desired zone of the stack.

The start of the process will not involve difficulties, the uppermost pan of the stack being accessible for the ignition which may be effected in the usual manner with admixture of inflammable fuel. Admixture of fuel to the charge or placing of a bottom layer of inflammable material on the grates may of course also be effected during the continuous operation, but may be dispensed with for many uses of the present process.

To ensure a uniform flowing of cooling medium through the grate tubes of the pan stack, the tubes may, if desired, be inclined slightly upwards in the direction of flow so as to contribute to the flow by thermosyphon effect. This can be done either by giving the tubes a slight inclination with respect to the top and bottom faces of the pan walls or by arranging the whole stack slightly inclined. Besides, if necessary, the cooling water circuit may pass through a reservoir ahead of the pump in which losses of cooling water due to leaking are covered and at the same time air bubbles, if any, may escape. Further, if desired, a tapping valve may be placed behind the closing cock of the circuit for applying a transitory suction to oppose leaking from the outlet of the uppermost pan of the stack incidental to the lifting of the connecting device 59.

Also in other ways the embodiment shown may be supplemented or modified within the scope of the invention. Thus, instead of resilient packing means on the pan flanges for tightening against

the surrounding shaft on the way out of the casing 31 it is possible to use shaft walls subjected to a resilient pressure, or other means than a direct sliding fit may be used, such as a sluice structure which may comprise pivoted or rotating tightening flaps or vanes, whereby a sliding fit, if any, will only be required at the corners. Further, the conveying of the pans may take place in other manners than by means of driven rollers, thus for example if sluice structures as mentioned above are used for tightening during the movement of the pans out of the casing, the pans themselves may be provided with rollers which run on stationary rails, the movement being effected by means of chains or in other suitable manner.

The invention may be applied for many purposes, such as sintering of iron ore or cement or in other fields where calcination, agglomeration, burning of calcium silicates, de-sulphurization or similar processes are involved.

I claim:

1. Draft sintering apparatus of the class described, comprising: at least three sintering pans each having side walls and a bottom grate for retaining a charge and permitting the downward flow of combustion air therethrough, said pans being disposed in vertically stacked relationship; elevating means acting on the lowermost of said pans for raising said pans in said stacked relationship; conveyor means for inserting a freshly charged pan beneath said raised stack; further conveyor means for removing the uppermost pan from said stack; and suction means disposed beneath the bottom of said stack for drawing combustion air downwardly through said stacked pans.

2. Draft sintering apparatus according to claim 1, wherein said side walls and grates of said pans have passageways for a cooling medium formed therein, said apparatus further comprising: circulating means for delivering a fluid cooling medium to said passageways; and separable connecting members interconnecting the passageways of adjacent pans in said stack.

3. Draft sintering apparatus according to claim 1, further comprising: enclosing means defining a low pressure zone surrounding the lower portion of said stack, said pans being vertically movable in pressure sealing engagement with said enclosing means; and air lock means communicating between the exterior and interior of said enclosing means, said first named conveyor means extending through said air lock means, whereby said freshly charged pan may be inserted beneath said stack without interrupting said downward flow of combustion air.

4. Draft sintering apparatus according to claim 1, further comprising: pan charging means disposed in proximity to said first named conveyor means; pan emptying means disposed to receive pans from said further conveyor means; and transfer means for moving an emptied pan from said emptying means to said first named conveyor means, said first named conveyor means including means for moving said emptied pan to be filled by said charging means.

5. Draft sintering apparatus according to claim 1, in which said elevating means includes means for lowering said freshly charged pan onto said suction means for engagement therewith and for lowering said raised stack into engagement with said freshly charged pan, whereby said freshly charged pan becomes the lowermost pan of said stack, and means engageable with said freshly charged pan after completion of said lowering movement for acting on said freshly charged pan to raise said stack, and wherein said further conveyor means includes means engageable with the uppermost of said stacked pans in the raised position of said stack for removal of said uppermost pan after said stack has been lowered.
